(57) **CLAIM**

The ornamental design for a jewelry clasp, as shown and described.

DESCRIPTION

FIG. 1 is a right, front environmental perspective view of a jewelry clasp showing my new design, the front being the open end of the clasp;

FIG. 2 is a right, rear perspective view thereof; and,

FIG. 3 is a right side elevational view the left side being a mirror image, thereof.

The broken line showing of the bracelet and the jump rings is for illustrative purposes only and forms no part of the claimed design.
